LINK FOR AN EXPANSIBLE BRACELET OR SIMILAR ARTICLE

Nathan Goodman, Forest Hills, N.Y., assignor to Baldwin Bracelet Corporation, New York, N.Y., a corporation of New York

Filed Aug. 27, 1959, Ser. No. 57,332

Term of patent 7 years

(Cl. D45—4)

Fig. 1.

Fig. 2.

Fig. 3.

Fig. 4.

Figs. 1 and 2 are respectively a top plan view and a side elevational view, of one of the links embodying my new design;

Fig. 3 is a sectional view taken on line 3—3 of Fig. 1; and

Fig. 4 is a perspective view of one of the links.

The design of the present invention is distinguished by the vertical end walls which are squared relatively to the various facets of the sides and top of the link, by the flat elongate portion projecting upwardly from between the inner ends of the inclined side facets, and by the central recess in said upstanding portion.

I claim:

The ornamental design for a link for an expandable bracelet or similar article, substantially as shown and described.
